ODOMETER MECHANISM

Filed Aug. 10, 1928

By Beckmore, Spencer & Flint
Attorneys

UNITED STATES PATENT OFFICE

JOSEPH ZUBATY, OF FLINT, MICHIGAN, ASSIGNOR TO A C SPARK PLUG COMPANY,
OF FLINT, MICHIGAN, A COMPANY OF MICHIGAN

ODOMETER MECHANISM

Application filed August 10, 1928. Serial No. 298,865.

This invention relates to measuring instruments and has been designed more especially as an improvement in the odometer mechanism used together with the speed measuring mechanism of a speedometer for vehicles.

The invention relates particularly to the transfer mechanism by which the number wheels of higher denomination are driven by the wheels of lower denomination and to that type of transfer mechanism making use of internal gearing.

An object of the invention is to provide an improved transfer pinion mounting.

Another object is to simplify the construction by the omission of the commonly used transfer pinion shaft.

As further objects, compactness, ease of assembly, low cost should be mentioned.

In the drawing:

20 Figure 1 is a view in front elevation with parts removed;

Figure 2 is a vertical section on line 2—2 of Figure 1;

25 Figure 3 is a fragmentary view in elevation showing the transfer pinion supporting frame and its mounting; and

Figure 4 is a detail in perspective.

Referring by reference characters to the drawing, numeral 9 is used to designate the 30 main supporting frame. It supports the speed indicating mechanism and on this frame is also supported the odometer or mileage recording mechanism. The mileage recording mechanism consists primarily of 35 two sets of figure wheels and two sets of star or transfer pinions. There is shown an upper set of figure wheels, one of which is designated by numeral 11. Only one of the wheels of the lower or "trip" set is shown. 40 It is indicated by numeral 15. A plurality of transfer pinions 10 are used between the adjacent wheels of each set whereby each wheel of higher denomination is intermittently rotated by the rotation of the next 45 adjacent wheel of lower denomination.

The driving means for the odometer is not a part of this invention and is not fully illustrated. There is shown a gear 12 which is the primary driving gear of the odometer. The speedometer will be provided as usual

with a driven shaft, frame 9 having a vertical bore therefor as at 6. This shaft is driven by a flexible drive shaft as usual and when so driven, it is used to drive the driven parts of the speedometer and also, through the instrumentality of intermediate gearing, to drive gear 12. Any suitable drive connection may be employed between gear 12 and the first figure wheel 11.

55 For driving the "trip" set of wheels there is an idler 13 driven by gear 12 and itself driving gear 14 on the shaft 16 of the trip set of wheels. Gear 14 drives the lowest denomination wheel 15 of the trip set through any suitable clutch connection. The frame has a passage for a reset spindle used to break the drive to the "trip" set of wheels. Said reset spindle carries means to restore the figure wheels to zero position. These 60 drive connections and the reset provision 70 form no part of the invention and the structure is not fully illustrated, being well known.

Between successive figure wheels of each set are stamped plates 17. Each plate 17 is apertured to be mounted on the shaft carrying the wheels, on shaft 16 as shown on Figure 3, for example. The plates 17 are substantially circular and of equal radius with the figure wheels. Each has an outwardly directed arm 18 extending from its periphery. The frame 9 is formed with a groove 19 which receives the arms 18. By the engagement of the plate 17 with the shaft and the groove 19 it is held in fixed position.

80 The stamped plate 17 has an arm 20 angularly bent therefrom as shown best in Figure 3 and Figure 4. It also has a portion opposite arm 20 depressed from the plane of the stamping as at 20'. Between parts 20 and 20' is a stub shaft 21 mounted in these parts and carrying a star pinion 10.

85 The figure wheels are circumferentially provided with figures from 0 to 9 and within their peripheries are provided with internal teeth co-operating with the transfer pinion 90 in such a way that a complete rotation of a wheel of lower denomination rotates the wheel of next higher denomination one-tenth of a revolution.

100 The specific arrangement for operating

through the transfer pinion while not a part of this invention, is shown in Figure 4 and may be briefly described. In this figure, numeral 15' is used to show in a fragmentary way a wheel of lower denomination and wheel 15 is a wheel of higher denomination. Within wheel 15' on its side adjacent wheel 15 are two teeth 31 extending axially and radially inward. Between these teeth is a deep space 32. The adjacent face of wheel 15 has a complete set of teeth 33. The transfer pinion has an intermediate web 34. On one side of the web are teeth 35 in driving engagement with teeth 33. Teeth 35 are also continued on the other side of the web, alternate teeth being elongated as at 35'. As the wheel 15' rotates two alternate long teeth 35' engage the inner periphery of the gear ring carrying teeth 31, whereby the pinion can not rotate thus holding wheel 15 from turning. When teeth 31 engage and drive teeth 35 the long tooth 35' overlies the deep space 32 so that the rotation of pinion and wheel 15 is possible. After wheel 15' turns so that its teeth 31 are beyond teeth 35, two long teeth again hold the pinion from turning.

It will be understood that the modification of the die cast frame to provide groove 19 is comparatively inexpensive. It will also be apparent that the stamping 17 is easily made and of inexpensive material. The assembly of the transfer pinion between parts 20 and 20' makes a complete unit easily slipped into position. The construction provides a very compact assembly and avoids the use of the usual frame carried transfer pinion shaft.

I claim:

In a measuring instrument comprising a frame, coaxial figure wheels, a shaft therefor and coaxial therewith, said figure wheels having internal teeth, a stamped plate mounted on said shaft between adjacent wheels in a manner to permit the rotation of said shaft relatively to said plate and having bearings to carry a transfer pinion, said plate further provided with a substantially radial arm and said frame having a groove to receive said arm and prevent rotation of said plate and pinion about the axis of said shaft.

In testimony whereof I affix my signature.

JOSEPH ZUBATY.
